United States Patent Office

Des. 181,002

Patented Sept. 17, 1957

181,002

ELECTROSTATIC CARD PRINTER OR SIMILAR ARTICLE

Walter Furlani, Endicott, and Jack W. Stringer, Johnson City, N. Y., assignors to International Business Machines Corporation, New York, N. Y., a corporation of New York

Application June 15, 1956, Serial No. 41,908

Term of patent 14 years

(Cl. D64—11)

Des. 181,002

PAGE 2

FIG. 2.

FIG. 3.

Fig. 1 is a front perspective view of an electrostatic card printer or similar article, embodying our new design.

Fig. 2 is a top plan view of the same.

Fig. 3 is a front elevation of the same.

Fig. 4 is a rear perspective view of the same.

The essential features of the design reside in the portions shown in full lines.

We claim:

The ornamental design for an electrostatic card printer or similar article, as shown and described.
